UNITED STATES PATENT OFFICE

FRANK C. DELI, OF CHICAGO, ILLINOIS, ASSIGNOR TO AUTOPOINT COMPANY, OF CHICAGO, ILLINOIS, A CORPORATION OF ILLINOIS

CAP FOR PENS

Application filed March 15, 1929. Serial No. 347,295.

My invention relates to caps for fountain pens, and is an improvement over the co-pending application of Deli and Groseclose, Serial No. 307,193, filed September 20, 1928.

It is well known that devices for securing fountain pens to the pockets of the user are very numerous and of divers designs and constructions.

However, the addition of a clip to a pen in the various designs heretofore utilized has proven relatively expensive from a manufacturing standpoint, and one of the objects of my invention is to provide a cap with a clip which is cheaply and easily assembled, and yet as strong and durable as necessity requires.

A further object of my invention is to provide means in the form of a decorative head for enclosing the various cooperating elements.

My invention will be more readily understood by reference to the accompanying drawings, in which

Fig. 1 is a plan view of a fountain pen cap construction in accordance with my invention;

Fig. 2 is a longitudinal sectional view taken on the line 2—2 of Fig. 1;

Fig. 3 is a longitudinal sectional view of the cap construction;

Fig. 4 is a perspective view of the cap;

Fig. 5 is a perspective view of the clip;

Fig. 6 is a perspective view of the sleeve; and

Fig. 7 is a perspective view of the head.

By reference to Fig. 2 it will be seen that my invention comprises substantially, the open ended cap 10, the plug 11, the clip 12 and sleeve 13, and the head 14.

In assembling the parts of my invention, the plug 11 is forced through the tube or cap 10 until the shoulders 15 on the lower end of the plug contact the shoulders 16 on the upper end of the cap, the shoulders thus acting as a limit stop.

The exposed portion 17 of the plug 11 is provided with an arcuate longitudinal groove 18 for the reception of the arcuate retaining member 19 on the upper end of the clip. The member 19 is simply inserted into

the groove 18 with the heel portion 20 resting in the notch 21 in the upper periphery of the cap 10. In forming the longitudinal groove 18, a grinding wheel of about 1½" diameter is utilized thus rounding the lower end of the groove. Experience has shown this to be the most desirable method of forming the groove, although the portion below the notch 21 serves no purpose. By forming the groove and retaining member of arcuate shape, the desired bearing surface is obtained with a minimum of material removed from the plug, thus tending to strengthen the plug head.

Thereafter, the sleeve 13 is slipped over the portion 17 and firmly pressed down until it rests upon the upper margin of the cap 10. The retaining member 19 is formed at a slight angle as seen in Fig. 5, so that a slight pressure against the clip 12 is necessary to flatten the member 19 to permit the passage of the sleeve 13 over it. Thus there is a constant outward tension against the inside of the sleeve, tending to maintain it firmly in position.

After the clip is positioned and securely anchored by the sleeve, the head 14 is screwed on over the portion 17, thus enclosing the retaining member and ring.

It is thus seen that I have provided a pen cap and clip of a novel construction being of economical manufacture and simple assembly. The head enclosing the retaining member and sleeve may be supplied in a contrasting color with that of the cap and a very attractive device will result.

Obviously, the tube 10 and plug 11 could be formed as one part if desired, and the groove 18 could be shortened to terminate below the threads, if desired, such groove being necessarily only the length of the retaining member.

Obviously, these and other modifications would occur to one practiced in the art, and I do not wish to be limited except as indicated in the appended claims.

I claim:

1. In a cap for fountain pens, the combination of an open-ended tube, a plug closing one end of said tube, a portion of said

- plug projecting beyond the end of said tube, said projecting portion having a longitudinal groove therein, a pocket clip, a retaining member formed on the upper end of said 5 clip, said retaining member adapted to be received in said groove, a sleeve adapted to fit over said plug and retaining member whereby to confine said clip, and a head adapted to fit over said plug and sleeve.
- 10 2. In a cap for fountain pens, the combination of a tube, a plug closing one end of the said tube, a pen clip, the upper portion of which is bent to provide a retaining member, means for securing said clip to said plug, and 15 a head for enclosing said plug, retaining member and securing means.
- 15 3. In a cap for fountain pens, the combination of a tube, said tube having a notch in the upper end thereof, a plug closing the upper 20 end of said tube, a pen clip, the upper portion of which is bent to provide a retaining member, means for securing said clip to said plug, and a head for enclosing said plug, retaining member and securing means.
- 25 4. In combination, a cap with open ends and a notch in one end, a grooved plug within and projecting beyond one end of said cap, a clip having an arm occupying said notch and a retaining member occupying the groove 30 in the plug, a sleeve surrounding the plug and holding said clip in place, and a head fitted over the projecting portion of the plug.
- 30 5. In combination, a cap with open ends and a notch in one end, a grooved plug within and 35 projecting beyond one end of said cap, a clip having an arm occupying said notch and a retaining member occupying the groove in the plug, a sleeve surrounding the plug and holding the said clip in place, and a head fitted over the projecting portion of the plug, said retaining member being bent 40 at an acute angle relative to said clip.
- 35 6. In combination, a cap with open ends and a notch in one end, a plug within and 45 projecting beyond one end of said cap, said plug having a groove in the projecting portion thereof, a clip having an arm occupying said notch and a retaining member occupying the groove in the plug, a sleeve surrounding 50 the plug and holding said clip in place, and a head fitted over the projecting portion of the plug.

In testimony whereof I have affixed my signature.
